UNITED STATES PATENT OFFICE.

WILLIAM R. KEAVANEY, OF WATERBURY, CONNECTICUT, ASSIGNOR TO THE CHASE COMPANIES, INC., OF WATERBURY, CONNECTICUT, A CORPORATION.

FLUSH WALL RECEPTACLE PLATE.

Application filed March 13, 1920. Serial No. 365,392.

To all whom it may concern:

Be it known that I, WILLIAM R. KEAVANEY, a citizen of the United States, residing at Waterbury, in the county of New Haven and State of Connecticut, have invented a new and useful Improvement in Flush Wall Receptacle Plates; and I do hereby declare the following, when taken in connection with the accompanying drawings and the characters of reference marked thereon, to be a full, clear, and exact description of the same, and which said drawings constitute part of this application, and represent, in—

Fig. 1, a view in elevation of a wall receptacle-plate embodying my invention.

Fig. 2, a view thereof with the door removed.

Fig. 3, an enlarged broken sectional view on the line 3—3 of Figure 1.

Fig. 4, an enlarged detached broken edge view of the door, showing the reduction of its hinge-leaf in thickness.

Fig. 5, a corresponding view showing the hinge-leaf as bent in to its final form over the integral pintle of the plate, the pintle being shown in transverse section.

My invention relates to an improved electric installation flush wall receptacle-plate of the type having a door, the object being to produce a fixture having the minimum number of parts, presenting a finished appearance, and reducing the cost to the minimum.

With these ends in view, my invention consists in an electric installation flush wall receptacle-plate having an integral pintle extending across the upper portion of the clearance-notch of its service-opening for the suspension of the door provided for closing the opening.

My invention further consists in certain details of construction as will be hereinafter described and pointed out in the claim.

In carrying out my invention as herein shown, I produce an integral pintle 4 at the time of punching or piercing the rectangular clearance-notch 5 leading out of the upper end of the relatively large circular service-opening 6 formed in the rectangular flush wall receptacle-plate 7 which, as shown, has bevelled edges 8 and is provided directly above and below the said service-opening with counter-sunk screw-holes 9 and 10 located in the major axis of the plate. The said pintle 4 at the time of its

production, is set back from the face of the plate 7 for a distance substantially equal to the thickness of the circular door or closure 11 so that when the same is in its closed position, its outer face will lie in the plane of the face of the plate. In setting the pintle back, as described, in this manner, its ends are virtually extended to a slight degree beyond the side-walls of the clearance-notch 5 and appear upon the face of the plate 7 in the form of indentations 12. In producing the integral pintle 4, its edges are rounded off, as shown in Figure 5, so as to permit the door to swing freely upon it.

The said door is formed at its upper end with an integral rectangular hinge-leaf 13 adapted to fit closely into the clearance-notch 5, and has its inner face cut away, as shown by Figure 4, to reduce its thickness to about one-half the thickness of the door proper, whereby it is easily bent rearward and downward to embrace the pintle 4, as shown in Figure 5. This reduction of the metal permits the leaf to be sharply bent, as at 14, so as to bring its upper end close to the top wall 15 of the notch 5 when the door is in its closed position, as shown in Figure 1.

I claim:

The combination with a flush-wall receptacle-plate formed with a service-opening, a rectangular clearance-notch leading out of the upper end of the said opening, and an integral pintle extending between the side walls of the said notch and positioned therein to form a clearance space between it and the upper wall of the said notch, of a door for the said opening formed at its upper end with a hinge-leaf closing the said notch and having the upper portion of its rear face cut away to substantially half the thickness of the said door, to permit the said leaf to be bent rearwardly and downwardly to embrace the said pintle, which is set back from the rear face of the said plate for a distance equal to the thickness of the main portion of the door and the lower portion of its hinge-leaf.

In testimony whereof, I have signed this specification in the presence of two subscribing witnesses.

WITNESSES:

CHARLES A. CURTISS,
L. L. CADWELL, Jr.
